UNITED STATES PATENT OFFICE.

DIMITRIOS PANTAZI, OF NEW YORK, N. Y.

SPRING-MOTOR.

1,223,102.

Specification of Letters Patent. Patented Apr. 17, 1917.

Application filed November 26, 1915. Serial No. 63,473.

To all whom it may concern:

Be it known that I, DIMITRIOS PANTAZI, a subject of the King of Greece, and a resident of New York, in the county of New York and State of New York, have invented certain new and useful Improvements in Spring-Motors, of which the following is a specification.

This invention relates to improvements in 10 spring motors and particularly of the type adapted to be used in connection with fans and other contrivances requiring a small amount of power to operate.

The principal object of the invention is 15 to provide a motor which will run for a greater length of time than is ordinary in constructions of this kind, the same occupying a relatively limited space in the base of the mechanism.

20 A second object is to provide means whereby the several springs may be wound simultaneously and with far less exertion than by the cranking methods usually employed.

These and other objects, which will be 25 come more fully manifest as the specification proceeds, are attained by the novel construction and combination of parts hereafter described and shown in the accompanying drawings forming a material part of the 30 specification, and in which:—

Figure 1 is a partial side elevation and sectional view showing an embodiment of the device, the section being taken substantially on line 1—1 of Fig. 2, and

35 Fig. 2 is an end elevation of the same, the casing being shown in section to better disclose the interior.

In the adaptation shown a base 10 may be supported by a number of pedestals 11 having 40 a wide foot 12, so that the apparatus may be secured upon any convenient surface.

Rising from the base are two pairs of brackets 14 in which are rotatably mounted 45 shafts 15, at one end of which and between the brackets are secured worm wheels 16 in such manner as to drive the shafts 15 when they are caused to rotate.

Motion is conveyed to the worm wheels 16 50 by means of the worms 17 rigid on the shaft 18 supported by brackets 19 transversely of the shafts 15, the shaft having one end extending beyond the casing and squared, as at 20, to receive the crank handle 21.

55 Mounted to rotate on the shafts 15 are two drums 25 in which are contained flat

spiral coil springs 26, one end, as 27, being secured within the drum while the other end 28 is fastened upon the periphery of a sleeve 29, the same being rigidly secured to the 60 shaft 15, so that when the shaft is rotated the spring will be wound. In order to convey motion from the oppositely disposed drums a number of pins 30 are used, the same passing through a spur gear 31, loosely 65 mounted upon the shaft 15.

It will be understood that each pair of drums are similarly mounted and have between them duplicate gears 31, both of which are adapted to mesh with the pinion 32 carried 70 on the short shaft 33, supported by the frames 34 and 35, which are secured to the base as indicated.

The upper end of the frame side 35 extends vertically its entire length while the 75 frame side 34 is bent, as at 36, and then turned up to meet the connecting bar 37 at the top.

Engaged with the pinion 32 is a train of gears leading to the pinion 40 secured upon 80 the shaft 41, the extending end of which has rigidly mounted upon it the fan blades 42 as shown, the shaft revolving in ball bearings carried in the frame sides 35 and 36.

In the sides of the gear 40 are formed a 85 number of openings 43 and adapted to engage with these openings are pins 44, carried by the detent 45, which is provided with a hub 46, slidable on the shaft 47 and constantly forced toward the gear by reason 90 of the spiral push spring 48.

All the foregoing mechanism is contained within a metallic casing 50 secured to the base at its bottom and arranged to neatly cover over all of the described mechanism, 95 except the handle 21, the fan head and the releasing mechanism shown at the top of the casing.

This mechanism consists of a handle 52, the same being pivoted in suitable brackets 100 53 and provided with an angular lug 54 adapted to make contact against the shifting detent 45 opposing the spring when in a vertical position and capable of being turned, as indicated by the arrow in Fig. 2, 105 whereupon the pins 44 will engage with the gear and prevent further motion of the clock train.

In operation the crank 21 is turned whereby the springs are tensioned, and the start- 110 ing lever 52 moved either up or down, so as to use the fan, or to have it remain quiet.

I am aware that the spring motors for similar purposes have been before used and therefore do not claim the idea as my own but what I do claim as new and desire to secure by Letters Patent, is:—

In a spring motor, the combination with two or more pairs of spring drums, said drums being arranged in the same horizontal plane one in advance of the other, shafts 10 upon which each pair of drums is rotatably mounted, worm wheels upon each of said shafts, coil springs engaged interiorly of said drums at one end thereof and with said shafts at the other, a shaft centrally between

each group of spring drums, gears combined with said drums co-acting to drive the second mentioned shaft, a train of gears driven by said second shaft, a shaft rotatably mounted transversely of said drum and gear shafts, worms on the last named shaft meshing with said worm wheels, means for manually rotating the last named shaft, and means for positively holding or releasing said gear train.

In testimony whereof I have signed my name to this specification.

DIMITRIOS PANTAZI.

Copies of this patent may be obtained for five cents each, by addressing the "Commissioner of Patents, Washington, D. C."
